V-BLOCK FORMATIONS**Norman S. Blocksage, Westmount, Weston, Ontario, Canada****Application November 3, 1953, Serial No. 390,037****11 Claims. (Cl. 90—59)**

This invention relates to improvements in devices of the nature of V-blocks, parallels and the like used in supporting, locating, inspecting and measuring work in machine practice, and more particularly to an improved V-block.

The principal object of the invention is to provide a V-block which will be adjustable in height so that the necessity of stacking parallels beneath the V-block to get the proper height adjustment is eliminated, thereby providing a very important saving in time and greatly facilitating handling of the block and stock with which it is being used.

A further important object is to provide an adjustable V-block as aforesaid which will be continuously adjustable over a wide range of adjustment so that it may be set at precisely the height desired, and to provide an arrangement whereby the work or stock to be held can be securely clamped to the V-block with the block at any position in its range of adjustment.

Another important object is to provide a V-block which can also function as an adjustable parallel for use in setting up and inspection to again provide a very material and important saving in time and to facilitate such work.

Still another object is to provide a V-block which will enable round stock to be quickly set up and securely held for end tapping and drilling, eliminating the present improvising required and unsatisfactory results obtained.

Again an important object is to provide a block which will enable prefabricating and T-welding to be quickly and easily carried out while ensuring complete accuracy in the angular relation of the parts.

Still a further object is to provide a V-block as aforesaid of economical and practical construction which can be adjusted very easily and quickly so that work can be conveniently adjusted to the setting of a drill press or other machine tool or the like rather than requiring the adjustment of the setting of the tool as in present cases, which tool adjustment again usually requires considerable time and care.

One important feature of the invention resides in providing a pair of co-operating members or block portions which define a V therebetween and which are relatively movable to alter the position of the apex of the V to enable the position of a piece of work or stock adapted to be supported in the V to be adjusted as desired.

More particularly the invention resides in forming the V-block as one member or block portion having an inclined face or surface and arranging a second member or block portion constituting a slide to operate up and down the inclined surface, the slide being formed with a face or surface oppositely inclined to the first-mentioned surface and forming therewith a V to support the shaft or other stock.

Another important feature of the invention resides in providing a clamp arrangement adapted to adjust to the relative positions of the two members or block portions to clamp the stock in the V.

A further important feature resides in forming the slide

2

to include an arm adapted to move in parallelism with a base or supporting surface of the first member throughout its travel so that the V-block also constitutes an adjustable parallel.

5 Another feature of importance resides in forming the clamping device as a support structure carrying a clamping member, the support structure having two sets of arms or support formations, one set to engage and support the clamping device from the slide and the other set having 10 pin projections riding in slots or grooves extending along the inclined face of the first block member or portion to enable the clamp device to follow movement of the slide and locate the clamping member opposite to the apex of the V formed between the slide and first block member regardless of the position of the slide.

A further feature resides in hinging the arms to enable the clamp device to be released from the members. Again a feature resides in forming the parallel arm of the slide with grooves so that the clamp can be used in co-operation with the slide arm only to clamp work thereto.

Still a further feature resides in forming the first member as a right angled Δ with the hypotenuse forming the inclined surface and the sides forming the right angle forming mounting sides for supporting the slide arm in a horizontal position for use of the device as a parallel and for supporting the slide arm in a vertical position for holding work for end tapping.

These and other objects and features will become apparent from the following description taken in conjunction with the accompanying drawings in which,

Figure 1 is a plan view of an adjustable V-block and parallel constructed in accordance with the invention.

Figure 2 is a side elevational view of the device of Figure 1.

35 Figure 3 is an end elevational view of the device of Figure 1 showing the clamping device in open position in dotted lines illustrating the manner in which it may be released from the block.

Figure 4 is a view similar to Figure 2 but showing the 40 slide member in a different position of adjustment, part of the slide and stationary member being broken away to illustrate the locking action of the slide.

Figure 5 is a side elevational view of the device employed to support stock for end tapping or drilling.

45 Figure 6 is an enlarged sectional detail on the line 6—6 of Figure 5.

Figure 7 is a small perspective view of the slide.

Figure 8 is a perspective view illustrating the use of a 50 pair of blocks constructed in accordance with the invention for supporting a shaft, the clamps being omitted.

Figure 9 is a side elevational view illustrating the use of the device in carrying out the formation of a T-joint.

With reference particularly to Figures 1 to 4, the adjustable block illustrated comprises a triangular frame 1 forming one member or portion of the block and a slide 2 forming another portion or member of the block.

The triangular frame 1 has two sides 3 and 4 which define a right angle therebetween, with the remaining side 5 forming the hypotenuse. Thus the frame 1 constitutes a right angled triangle, and preferably a right-angled isosceles triangle.

Each of the sides 3, 4 and 5 is provided with a slot, sides 3 and 4 having slots 6 to receive clamping bolts 7, Figures 4 and 5, to enable the frame to be clamped to a table or other support surface 8.

The hypotenuse 5 has a slot 9 to receive the clamping bolt or pin 10 of the slide 2, hereinafter more particularly described.

70 The slide 2 is arranged to slide on the face 11 of the hypotenuse 5 of the triangle, and extending adjacent and parallel to the face 11 on each side of the member

1 is a groove 12, or the grooves 12 may connect to form a slot.

A scale indicated at 13 is disposed between the grooves 12 and the face 11.

The slide 2 has a base portion 14 which rides on the face 11 and which, as best shown in Figures 4 and 7, preferably presents a key 15 adapted to ride in the slot 9 to guide the slide 2. The slide 2 is provided with a laterally extending arm 16 reinforced by a rib 17 extending beneath the arm 16 to the base 14.

The upper face of the arm 16 indicated at 18 is arranged to extend and lie precisely parallel with the bottom face 19 on the side 3 of the triangular frame 1 and hence precisely at right angles to the face 20 of the side 4 of the triangle.

Extending between the upper face 18 of the arm 16 and the bottom face of the base 14 of the slide is a face 21 which forms the end of the slide face 14, and this face or surface 21 is precisely perpendicular to the face 11 of the hypotenuse 5 of the triangular frame, being oppositely inclined to the latter face to define therewith a V.

The apex 22 of the V will be located at a point on the scale 13 corresponding to the position of the slide 2, and as will be seen from Figures 2 and 4, may be varied at will along the scale 13 as the slide 2 is moved up or down the face 11 of the hypotenuse of the triangle.

The locking device for locking the slide 2 in desired position of adjustment on the face 11 of the triangle is best illustrated in Figures 4 and 6. This device comprises a pin 23 operating in a bore 24 extending transversely of the slide base 14 and having an eccentric portion 26 operating in a central chamber 26', the pin being rotated by means of an operator 27.

The clamping pin 10 is provided with a sleeved head 28 within which is received the eccentric portion 26 of the pin 23. The lower end of the pin 10 is threaded and carries a locking nut 29 which preferably has a reduced portion 30 entering the slot 9 of the hypotenuse of the triangle.

By operation of the pin 23 through the operator 27 the eccentric action is adapted to move the lock nut 29 towards the inner face 31 of the hypotenuse 5 of the triangle to clamp the slide to the triangle and to move away from the face 31 to release the slide for adjustment on the face 11.

Formed at each side of the arm 16 of the slide and extending parallel to the face 18 is a groove 32. If desired the grooves 32 could communicate where structural strength permits to form a slot through the arm 16.

The upper face 18 of the arm 16 is preferably provided with both a central longitudinally extending shallow deformation 33 and a transverse deformation or groove 34. The purpose of these grooves 33 and 34 will hereinafter more particularly appear.

While the V-block constituted by the triangle 1 and the slide 2 may be formed of such material as may be desired, it is preferable that they be sand-cast of spatter-proof steel so that they may be used for welding purposes without deleterious effects, as will be more particularly pointed out in connection with Figure 9.

In conjunction with the arrangement of the triangular frame 1 and slide 2 is the clamp device 35 which enables a piece of stock 36, e. g. a shaft, to be secured in the V defined between the faces 11 and 21, as shown in Figures 2 to 4, or to be clamped in the V-grooves 33 and 34 of the slide arm 16, as shown in Figures 5 and 9.

As illustrated, the clamp device comprises a central body or spindle supporting portion 37 which is suitably threaded to receive and coat with a clamp screw 38 having a clamping foot 39 and actuated by the operator 40.

Pivoted on pins 41 at opposite sides of the spindle-supporting portion 37 of the clamp are two sets of arms 42 and 43 which arch downwardly from the central portion 37 and which carry at their lower ends respectively pin projections 44 and 45 which engage respectively in

the grooves 12 and 32 to support the clamping device from the triangle 1 and slide 2.

It will be noted that the axes of the pins 41, on which the arms 42 and 43 are pivoted, extend parallel to the arm 16 of the slide, so that under the reactive thrust imparted, as the clamping foot 39 of the clamp screw 38 engages the stock or work 36 exerts an upward pressure on the central portion 37 of the clamp device, there will be no force acting to open or spread the arms 10 from their solid line to their dotted line position as shown in Figure 3. Rather the force acting upwardly on the central clamp portion 37 will act to more securely anchor the pins 44 and 45 of the arms 42 and 43 in their respective slots or grooves 12 and 32.

15 Suitable springs 46 are provided to maintain the arms 42 and 43 in their "closed" position of Figure 3 when the clamping foot 39 of the clamp is withdrawn from the work 36 to eliminate the reactive thrust on the central portion of the clamp 37.

20 The fact that the clamp device 35 will maintain its clamping position for any position of the slide 2 can best be explained in connection with Figure 4. As shown in this figure, the pins 45 of the arms 43 are against the inner ends of the grooves 32 in the slide arm 16. The pins 44 of the arms 42 project into the grooves 12 at a point approximately aligned with the grooves 32.

Under the reactive thrust on the central or body portion 37 of the clamp as the clamp screw 38 clamps the stock 36 in the V the central clamp portion 37 is urged

30 upwardly imparting a tendency through the depending arms 42 and 43 to reduce the spacing between the pins 44 and 45, that is, to draw these pins together. As the pins 45 are at the inner ends of the grooves 32 their position is fixed and to decrease the separation between

35 the pins 44 and 45 the pins 44 would have to travel down the grooves 12 and not up the grooves, as would on first consideration appear. However, since the arms 42 and 43 are rigid and the spacing of the pins 44 and 45 fixed and since the pins 44 cannot move down

40 the grooves 12 without bringing the central clamp portion 37 closer to the work against the reactive thrust of the clamp screw, the pins 44 maintain a fixed position in the grooves 12 corresponding to the position of the slide 2.

45 It will be noted that with the locking action afforded by the pin 23 and clamping bolt 10, clamping the slide 2 to the hypotenuse 5 of the triangular frame with an eccentric locking action, the location of the lock may be made centrally between the upper end or face 21

50 of the slide and the lower end of the slide indicated at 47. That is, by providing the side action lock operated from the side, the lock can be so centrally located without interference with the slide arm 16. In this way effective clamping between the slide and triangle may be

55 obtained with uniform clamping force being applied adjacent the slide ends 21 and 47 to eliminate any rocking of the slide under clamping action.

In use a set of the blocks may be employed, as illustrated in Figure 8, to support the stock or shaft 36, with

60 the height of the stock above the support table or surface being determined by the position of the apex 22 of the V's. Such support of the stock may be for the purpose of measuring, inspecting or actually working on the stock, and of course the clamps, which are omitted from Figure 8, will securely hold the stock in position on the V-blocks.

65 Alternatively, as shown in Figure 5, the clamp device 35 may be removed from the triangular frame 1 by spreading the sets of arms 42 and 43, as shown in Figure 3, and then arranging the clamps so that all of its pins

70 44 and 45 engage in the grooves 32 of the lateral arm 16 of the slide. Then by turning the triangular frame 1 through 90° and bolting it to the table 8 the stock 36, upon being introduced into the groove 33, is held in perpendicular relation to the table 8 for end drilling or 75 tapping by the tool 48.

Thus the block forms an extremely convenient means of supporting, precisely perpendicular, eliminating the improvising now required for supporting work in such a manner.

Figure 9 illustrates the use of two of the V-blocks to support two pieces of work in perpendicular arrangement for T-welding. The left-hand block is shown as supporting its work piece on the lateral slide arm 16 to extend in a direction accurately parallel to the table 8, while the right-hand block is supporting its work piece 36 in a position accurately perpendicular to the table 8 and in abutment with the end of the other work piece. The work pieces may then be tacked together for permanent welding in a different location or may be welded in situ.

It will also be appreciated that in many instances it may be convenient to clamp the work piece in the other groove 34 of the lateral arm 16, such as when using the V-blocks as adjustable parallels.

It will be understood that various details of construction may be altered without departing from the scope of the appended claims.

What I claim as my invention is:

1. A V-block comprising a member having an inclined face, a second member sliding on said inclined face and presenting an inclined face forming with the aforesaid face a V, means to lock said members in desired relative positions, and clamp means having a clamping member and a support formation engaging and co-operating with the first-mentioned members to locate said clamping member opposite the apex of said V independent of the relative position of said first-mentioned members.

2. An adjustable V-block and parallel comprising, a member having a support base and a face inclined relative to said support base, a slide sliding relative to said inclined face and presenting an inclined face defining with the aforesaid inclined face a V and having an arm extending away from said V and presenting a longitudinal upper surface meeting and extending from the upper edge of said inclined face and precisely parallel to said base.

3. An adjustable work-supporting block device comprising, a support block portion having an accurate supporting face and an inclined face inclined relative to said supporting face, and a slide block portion sliding on said inclined face and presenting an inclined face defining with the aforesaid face a work-supporting V and presenting a work-supporting face meeting and extending from the upper edge of said slide block inclined face and accurately parallel to said first-mentioned supporting face and spaced therefrom according to the position of said slide block portion on the inclined face of said support block portion, means for locking said slide block portion in desired position on the inclined face of said support block portion, and means for clamping a piece of work in position relative to said block portions comprising a clamp member and a support formation adapted to engage and cooperate with said support block portion and said slide block portion to locate said clamping member opposite the apex of said V independent of the relative position of said support block and slide block portions.

4. An adjustable V-block or the like comprising, a support block portion having an inclined face, and a slide block portion sliding on said face and presenting an inclined face defining with the aforesaid face a V, a slot at each side of the inclined face of said support block portion extending parallel to said latter inclined face, a clamp device having a support structure provided with pin projections riding in said slots, and means engaging said slide block portion, and a clamp member disposed opposite to and movable towards and from the apex of said V adapted to clamp a work piece in said V, said pin projections riding in said slots upon movement of said slide to maintain said clamp member opposite to the apex of said V.

5. An adjustable V-block comprising, a right angled triangular member adapted to be mounted on either of

5 10 15 20 25 30 35 40 45 50 55 60 65 70 75

the sides defining the right angle on a support surface, a slide sliding on the hypotenuse of said member and presenting a face defining with said hypotenuse a V, the position of the apex of which is variable along said hypotenuse upon movement of said slide, means for clamping said slide in adjusted position on said hypotenuse, said triangular member having groove means extending along said hypotenuse, and a clamp having a body portion through which a screw-threaded clamping member is adapted to operate towards and from the apex of said V and a pair of opposed support portions, one to engage said slide and the other carrying pin means engaging in said groove means, said groove means locating said pin means under reactive thrust imparted to said clamp body portion under clamping of a work piece in said V to support said screw-threaded clamping member directly opposite the apex of said V independent of the position of said slide on said hypotenuse.

6. An adjustable V-block and parallel comprising a right-angled triangular block member adapted to be mounted on either of the sides defining the right angle, a slide sliding on the hypotenuse of said block member and presenting a face forming with said hypotenuse a V, said slide having an arm presenting a face parallel to one of the sides of said triangular block member defining said right angle, means for locking said slide in desired position of adjustment on said hypotenuse to vary the distance of the apex of said V and said latter face from said latter side, said triangular block member being formed with grooves extending on each side thereof parallel to said hypotenuse, and a clamp comprising a central body portion through which operates a work-clamping member, a support formation engaging and supporting said body portion from said slide, and a support formation comprising a pair of arms carrying pin projections riding in said grooves to follow movement of said slide and supporting said body portion from said triangular member.

7. A device as claimed in claim 6 in which said clamp support formations comprise two sets of paired arms pivoted to opposite sides of said central body portion to swing about axes extending in the direction of said slide arm, two corresponding arms of said sets forming said pin-carrying arms supporting said clamp from said triangular member and the other two corresponding arms carrying pin projections, and said slide having recess means to receive said latter pin projections, said sets of arms being swingable to an open position to release said clamp from said triangular member and slide.

8. A device as claimed in claim 7 in which said slide is formed with grooves extending parallel to and at opposite sides of said face presented by said arm, said latter grooves forming said recess means, and said latter face is formed with groove means and the pin projections of said two sets of paired arms are adapted to engage in said grooves at opposite sides of said arm to support said clamp from said arm in position to clamp a piece of work thereto.

9. An adjustable V-block or the like comprising, a pair of relatively movable members presenting oppositely inclined faces defining a V therebetween, means for locking said movable members in desired relative position, one of said members having groove means extending parallel to its inclined face, and clamp means having a central work-clamping screw support through which a clamp screw operates carried on depending arm means supporting said clamp from said members with said clamping screw opposite the apex of said V, said arm means including an arm formation carrying pin means engaging in the groove means of said grooved member, and an arm formation engaging the other of said members.

10. A V-block comprising a pair of relatively movable members defining a V therebetween, with the apex thereof of varying with relative movement of said members,

and a clamping device comprising a support structure including a pair of depending legs engaging each of said relatively movable members with at least one pair of legs being supported on one of said members for sliding movement along one face of the V defined between said members upon relative movement of said members, and a clamping member disposed by virtue of the sliding of said legs opposite the apex of said V independent of the relative position of said relatively movable members.

11. A V-block comprising a pair of relatively movable members presenting faces defining a V therebetween, means for locking said members in desired relative position to locate the apex of said V, and a clamping device comprising a support structure including a pair of de-

pendent legs engaging each of said relatively movable members with at least one pair of legs being supported on one of said members for sliding movement along one face of the V defined between said members upon relative movement of said members, and a clamping member disposed by virtue of the sliding of said legs opposite the apex of said V independent of the relative position of said relatively movable members.
